[57] CLAIM

The ornamental design for combined overcap and aerosol actuator, as shown.

DESCRIPTION

FIG. 1 is a front elevational view of a combined overcap and aerosol actuator showing my new design;
FIG. 2 is a rear elevational view thereof;
FIG. 3 is a right side elevational view thereof, the left side being a mirror image;
FIG. 4 is a top plan view thereof;
FIG. 5 is a bottom plan view thereof.

FIG. 1***FIG. 2******FIG. 3******FIG. 4******FIG. 5***
